[21] Appl. No.: 866,177

[57] CLAIM

The ornamental design for a closure strap for a carrying case, substantially as shown and described.

DESCRIPTION

[22] Filed: Dec. 30, 1977

FIG. 1 is a perspective view of a closure strap for a carrying case showing my new design;
FIG. 2 is a front elevational view thereof, the opposite side being plain and unornamented;
FIG. 3 is a left side elevational view thereof;
FIG. 4 is a top plan view thereof; and
FIG. 5 is a bottom plan view thereof.
